UNITED STATES PATENT OFFICE.

ALVA J. FISHER, OF EVANSTON, ILLINOIS, ASSIGNOR TO HURLEY MACHINE COMPANY, OF CHICAGO, ILLINOIS, A CORPORATION OF ILLINOIS.

WASHING MACHINE.

Original application filed October 7, 1921, Serial No. 505,977. Divided and this application filed January 22, 1923. Serial No. 614,077.

To all whom it may concern:

Be it known that I, ALVA J. FISHER, a citizen of the United States, residing at Evanston, in the county of Cook and State of Illinois, have invented certain new and useful Improvements in Washing Machines, of which the following is a specification.

This invention relates to laundry washing machines and more particularly to the rotating drum or container for tumbling or agitating the laundry, and the main object of the invention is to construct the drum or container of metal stampings and parts which are quickly and easily assembled and cheaply manufactured, while at the same time the drum combines and embodies the efficiency, minimum wear and tear on the laundry, avoidance or prevention of warping, distortion, rust or corrosion of the parts and ease of repair. The invention also embodies new and useful improvements in the closure means for the rotating drum, and the appended claims are more particularly directed to such improvements, the present application being a division of my copending application, Serial No. 505,977, filed October 7, 1921, in which the remaining features of the invention are claimed.

In the drawings, Figure 1 is a sectional view taken through a washing machine, the section being taken near the right hand end of the machine to show the rotating drum, embodying the present invention, in end elevation; Fig. 2 is a cross-section through part of the drum, shown in Fig. 1; Figs. 3 and 4 are detailed sections taken on lines 3-3 and 4-4, respectively, of Fig. 1; Fig. 5 is a longitudinal section through part of the drum, as on the line 5-5 of Fig. 2 and with the middle portion of the drum broken away; Fig. 6 shows a full sized section taken through one of the end portions of a wall section and the adjacent end portion of the head of the drum; Fig. 7 is a transverse section through a portion of the door or cover and the parts in proximity with its rear edge, the section being taken as on the line 7-7 of Fig. 5; Fig. 8 is a perspective view of the forward portion of a side plate of the door or cover; Fig. 9 is a section on the line 9-9 of Fig. 4; Fig. 10 is a section on the line 10-10 of Fig. 7; Fig. 11 is a perspective view of a fragment of one of the heads and

Fig. 12 is a section on the line 12-12 of Fig. 7.

Referring to Fig. 1 of the drawings, the washing receptacle or tub 1 is preferably of the general type illustrated in my copending application, Serial No. 338,511, filed November 17, 1919, and comprises two metal end frames 2 and a tub consisting of a cylindrical sheet metal wall 3, ends 4, and a door or cover 5, hinged at 6 and provided with a handle 7 near its front edge to facilitate the opening and closing of the cover. The laundry tumbling or agitating drum 8, embodying the present invention, is rotated in the tub about trunnions 9 and 10 (Figs. 1 and 2) by an electric motor or other suitable means not shown. The trunnion 9 projects from a plate 11 fastened to one end of the drum 8 and is adapted to seat in a bearing (not shown) on the corresponding end 4 of the tub. The trunnion 10 projects from the other end of the tub into a bearing 12 on the plate 13 fastened to the adjacent end of the drum and is held therein by a slide 15 (Fig. 1) which is operated by a lever 14 to permit removal of the drum from the tub, as is well understood in the art.

The drum 8 comprises ends or heads 17, baffles or agitators 18, a plurality of curved sections 19 forming the cylindrical head or wall, and a cover or door 20. The ends or heads 17 are formed of sheet metal discs stamped by dies to give them the required shape or contour. Stamped centrally in each head 17 is a five-point star 21 having a circular center portion with the points of the star forming radiating ribs, the star depressions being formed to add rigidity and strength to the heads. The inner sides of the plates 11 and 13, which are riveted or otherwise fastened to the heads, conform to these depressions. Adjacent the periphery 95 of each head is formed an annular rib 23 (Fig. 6) forming a circular groove 24 opening inwardly and an overhanging flange 25.

The four sections 19, forming the cylindrical wall of the drum or cylinder are alike in construction and each is formed from a blank of sheet metal, being given the desired shape by means of suitable dies. These curved sections 19 and the heads 17 are preferably formed of the same thin sheet metal, which possesses considerable strength while

at the same time it has rust-proof and non-corrosive characteristics. The transverse edge portions of the sections are curved outwardly and then towards each other to form curve edges and overhanging flanges 26 so that when the sections are assembled on the head the curved edges seat firmly in the grooves 24 in the heads and flanges 26 press against the flanges 25 to assure a tight fit between the ends of the sections and the heads. The longitudinal edge portions of the sections 19 are provided with grooves 27 (Figs. 2 and 7) and the outer walls 28 of the grooves are curved cylindrically.

It will be observed that channels or grooves 29 (Fig. 6) somewhat V-shaped in section are on the inside of the drum in the corners formed by the union of the sections 19 with the heads 17 and contiguous with the line of contact 30 of the sections with the heads. This feature, the principle of which is followed at various places throughout the drum is a very important one, its purpose being to prevent pieces of laundry, and particularly garments or fabrics of delicate or fine texture, such as laces and silks, from becoming fastened, caught or cut on sharp edges or between the contacting surfaces or edges of the sections and heads and consequently torn or damaged. In the present invention the line of contact between any two surfaces or parts, such as that between the sections and a head do not contact with the laundry because the narrow channels, adjacent the line of contact, such as the channels 29, keep or space the laundry away from the same.

The baffles or agitating plates 18 are preferably formed of some light but strong and rigid metal, such as an aluminum alloy which is non-rusting and non-corrosive. The baffles are corrugated or ribbed lengthwise, as shown in Figs. 2 and 7, to give them added strength. The ends of the baffles are of uniform thickness (transversely of the baffles) and the corrugated portions merge therewith to avoid sharp corners. These ends of the baffles are seated in equi-spaced depressions 31 (Figs. 2, 7 and 12) which are formed in the heads 17. These depressions have the same depth as and merge with the grooves 24 and are widened or flared at their outer or merging ends to accommodate the ends of the grooved edge portions of the sections 19, it being understood that the turned transverse end portions of the sections terminate short of the grooved edge portion, as indicated at 32 (Fig. 7). The side walls of the depressions are inclined to provide the channels or grooves 33 which prevent the laundry from probably getting fastened between the contacting edges of the baffles and heads, as explained above.

The inner longitudinal edge of each baffle plate is provided with an integral bead 34,

substantially semi-cylindrical in cross-section, and a corresponding bead 35 is provided on the outer edge, but each bead 35 is further provided with a ledge or projecting rib 38 extending the length of the baffle plate. The baffle plates at the front and rear edges of the door or cover opening are constructed slightly differently than the other baffle plates, the ribs 38 of the former being provided with a single over-hanging flange 39 while the ribs 38 on the other baffle plates are T-shaped in section, thus providing two flanges 39. The longitudinal edges of the sections 19 project into the grooves 37 formed by the flanges 39 and the beads 35, the curved marginal portions 28 of the sections being in contact with the complementary, cylindrically-curved surfaces 41 of the beads. Channels 42 are provided between the beads and the portions 28 adjacent the line of contact to prevent any laundry from being caught or pinched or cut as explained above. As shown in Figs 3 and 4 the flanges 25 of the heads fit in recesses or cut-away portions 36 in the ends 90 of the ribs or ledges 38.

The ends of the baffles 18 are equipped with bosses 44 provided with screw threaded openings into which headless screws 45 are screwed (Figs. 3, 4, 9 and 10). As shown in Fig. 9 one side of each screw is flattened and after the screw has been placed in the opening the side of the boss 44 opposite the flattened side of the screw is also flattened in any desired manner so that it will positively prevent the screw from working loose or being withdrawn from the boss. The screws project through apertures in the bases of the depressions 31 in the heads and their projecting ends carry washers 47 and nuts 48, the screws, nuts, and washers being the only devices employed for fastening the heads securely to the baffle plates and holding the baffle plates, the heads and the wall sections 19 in assembled condition. The nuts 48 on the screws for the baffle plates adjacent the door opening are provided with integral sleeves or bosses 50 for purposes to be described later, it being understood that the other nuts 48 are not provided with these bosses.

The main panel of the door or cover 20 is formed of the same kind of sheet metal as the sections 19 and is curved on the same radius to complete the cylindrical form of the drum. It is approximately of the same width (from front to rear) as each of the sections 19, but is somewhat shorter in length (from side to side) as shown in Fig. 5. The front edge of the door is rolled outwardly about the stiffening rod 53 (Fig. 2) which is as long as the main panel and the rear edge of the main panel is bent inwardly to form a flange 54 having a cylindrical portion contacting with the forward semi-cylindrical portion.

The inner longitudinal edge of each baffle plate is provided with an integral bead 34,

drical portion 55^a of the bead 35 of the adjacent baffle plate (Fig. 7). Riveted or otherwise secured to the transverse edges of the main panel of the door are plates 55 (Figs. 5 1, 2 and 7), preferably thicker than the main panel in order to give added strength and rigidity to the door and to serve as pivot or hinge plates. The portions of the flanges 25 (Fig. 11) on the heads within 10 the door opening are rolled into the grooves 24 to form smooth edges and the plates 55 are provided with grooves 56 which fit over these rolled edge portions of the heads when the door is closed.

15 The sleeves or bosses 50 (Fig. 10) of the nuts 48 on the outer screws in the baffle plate at the rear edge of the door project through flared openings 57 in the rear enlarged ends 20 of the overhanging flanges 56^a of the plates 55 and serve as pivots for the door. The forward ends of the flanges 56^a have circular 25 depressions in which are secured metal discs 58 (Fig. 8) the discs and plates being provided with cut-away portions forming shoulders 59 with which noses or projections 60 on latches 61 engage to lock the door in closed position (Figs. 1 and 3). The latches 61 are pivoted on the bosses 50 of the inner 30 nuts 48 carried by the screws on the baffle plate at the front edge of the door and the bosses on the outer nuts project through slots 63 in the latches, which have finger pieces 64 to facilitate their manipulation. 35 Springs 67 at one end are coiled about the bosses on the outer nuts and the opposite ends of the springs after passing under the bosses on the inner nuts press against flanges 65 to force the latches into latching position. When the door is closed the curved edges of 40 the plates 55 under the shoulder 59 engage inclined edges 66 on the latches to force the latches forwardly until the shoulders 59 and 60 are in registry when the springs move 45 the latches into latching position, it therefore being unnecessary for the operator to touch the latches while the door is being closed.

50 Mounted on the bosses 50 of the nuts on the baffle plate at the rear edge of the door are springs 68 having projecting bent portions 69 which contact with the rear edges 70 of the flanges 56^a of the plates 55. The springs 68 are so tensioned that, when the latches are operated to release the door, they 55 move the door to the partially opened position shown in dash lines in Fig. 7. The door 20 may then be raised or fully opened by hand to the position represented by the 60 dot-dash lines in Fig. 7. This is a very important feature of the invention as it requires or warns the operator to close the door of the drum tightly before the machine is operated. With the present construction 65 the operator may close the door and think that it is latched, but on removing her hand

the door, if not actually latched, will spring partially open, giving full warning that it was not latched in closed position.

It will be noted that when the door is closed the rear edge of its flange 54 is flush 70 or contacts with the flat surface of the baffle plate immediately under or contiguous to the curved portion 55^a of the bead, this close fit being very desirable to avoid threads of the laundry from being caught or fastened 75 between the flange and the baffle plate. The cylindrical surface of the flange 54 is also in contact with the cylindrical surface 55^a while the door is being closed for the same purpose. When the door is fully opened it 80 may, if desired, be resiliently retained in such position by the engagement of its flange 54 against the top edge of the rib 38 of the baffle plate, the yielding character of the flange 54 being availed of to accomplish this 85 result.

The main panel of the door and the sections 19 are provided with numerous apertures 70 (Figs. 5 and 6) which are preferably arranged in parallel longitudinal and 90 transverse rows. The function of these holes or apertures as is well known in the art, is to permit circulation of the air and water. The metal around the holes is pressed or stamped outwardly to form 95 frusto-conical depressions 71 with the holes at the apexes and the metal at the bases of the depressions is stamped inwardly to form annular ribs 72. The metal at the edge of each hole is rolled outwardly back upon itself to form a smooth continuous rounded 100 edge about the hole. This construction, while simple embodies very important advantages. The integral rolled edges present 105 smooth rounded surfaces bounding the holes and free from the cracks, corners, or sharp edges within the holes and on the inside of the drum and therefore cannot cut or catch the laundry.

In Fig. 10 I have shown the outer ends 110 of the openings through the nuts 48 filled with solder or other soft metal 74, all of the nuts being preferably treated in this way to prevent them from working loose. It is obvious however that this soft metal does not 115 prevent the nuts from being readily removed by a wrench when it is desired to disassemble the drum or remove a part thereof.

120 From the above description it will be apparent that its drum is quickly and easily assembled and disassembled, the only fastening devices being the screws 45 and the nuts 48, as the sections 19 are held in position by reason of the engagement of their transverse and longitudinal edges in the grooves 24 in the heads and the grooves 37 in the baffle plates. The heads and sections 19 are 125 formed of very thin sheet metal and, therefore, have a somewhat resilient character so 130

that when the parts are assembled the curved or rounded transverse edge portions of the sections fit tightly and firmly in the grooves 23 and the curved marginal portions 5 28 are firmly pressed against the complementary curved portions 41 of the beads on the baffle plates. This affords a very simple and yet very rigid drum construction which prevents any torsional or twisting 10 movement of the drum, that is to say, any relative movement between the heads, it being important to prevent such torsional movement as the drum is driven from only one head or end. At the same time the 15 drum has no parts which can become warped or distorted, and laundry of the finest texture or character is prevented from being caught or fastened between the parts by virtue of the narrow channels or grooves formed adjacent the lines of contact of the parts. The edges around the holes 71 are smooth and rounded, presenting no crack or sharp edge which might catch or cut the laundry and the metal around the holes is 20 stamped or formed so as to increase the efficiency of the drum. Should a part of the drum become damaged it may be readily repaired or replaced by a new part, as the drum is easily and very quickly disassembled and assembled, it being merely necessary to remove and then replace the nuts 48. It is apparent that as the wall sections and 25 heads are made from sheet metal stamped by dies and that as the parts are merely fastened together by a few screws and nuts the cost of manufacture is very low and the parts may be easily packed and cheaply transported in a "knock-down" condition and then quickly assembled at their destination.

While I have shown and described a cylindrical drum it is obvious that this casing or container may be of any desired shape and form and embody various features of the 45 present invention. I have described above one form of embodiment of my invention but it is to be understood that the invention is susceptible of various modifications and changes all coming within the scope and 50 spirit of my invention, as defined in the following claims:

1. In a washing machine, the combination of a casing having an opening, a drum mounted to be operated therein, a door pivoted on the drum and adapted to open into said opening, latch means for holding the door closed, and spring means for holding the door open when it is not in latched position.

2. In a washing machine, the combination of a casing having an opening, a drum mounted to be operated therein, a door pivoted on the drum and adapted to open into said opening, latch means for holding the door closed, and spring means of sufficient strength

to only partially open the door and hold it partially open when it is not in latched position the door being adapted to be manually opened the rest of the way independently of the spring means.

3. In a drum for washing machines, the combination of metal heads, a metal baffle, devices on the baffle projecting through the heads for securing the heads to the baffle, and a door on said drum pivoted on said securing devices.

4. In a drum for washing machines, the combination of metal heads, a metal baffle, devices on the baffle projecting through the heads for securing the heads to the baffle, 80 a door on said drum pivoted on said securing devices, latch means for holding the door in closed position, and springs mounted on said securing devices for holding the door opened when not in latched position. 85

5. In a drum for washing machines, the combination of heads, a wall having a door opening, a baffle at each edge of said opening, a door, spring means for holding the door in opened position, latch means for holding the door in closed position, and devices for securing the heads to the baffles, the devices for one baffle also supporting the spring means and pivotally supporting the door and the devices for the other baffle 95 supporting the latch means.

6. In a drum for washing machines, the combination of heads, a wall having an opening therein, a door for closing said opening, side plates secured to said door and having inner and outer flanges forming grooves fitting over the edges of the heads when the door is in closed position, and means projecting through the outer flanges of said side plates for pivoting the door on the outside 100 of the drum.

7. In a drum for washing machines, the combination of heads, a wall having a door opening, a door having an inwardly extending flange at its rear edge, means for pivotally mounting the door on the outside of the drum, and a member extending between the heads and having a rounded portion adjacent the pivotal axis of the door and in sliding contact with the rear flange of the door during opening and closing movements thereof.

8. In a drum for washing machines, the combination of heads, a wall having a door opening, a door pivotally mounted on the drum and having a curved flange, and a member extending between the heads and having a portion within the drum curved complementary to and in sliding contact with said curved flange during opening and closing movements of the door.

9. In a drum for washing machines, the combination of heads, a wall having a door opening, a door pivotally mounted on the drum, and a baffle secured at its ends to the 130

heads and having a rounded portion adjacent the pivotal axis of the door and in sliding contact with the rear edge of the door during opening and closing movements of the door.

10. In a drum for washing machines, the combination of heads, a wall having a door opening, a door pivoted at its rear end on the drum and having a flange on its rear portion and a baffle plate having a portion with which the rear edge (formed by the thickness) of the flange firmly engages when the door is closed and also having a curved portion with which the flange slidingly engages during opening and closing movements of the door.

11. In a drum for washing machines, the combination of heads, a wall having a door

opening, a door pivotally mounted on the drum and having a curved flange at its rear edge, and a member extending between the heads and having on one side a portion curved complementary to and in contact with said curved flange and on the other side a groove in which the end of said wall is located.

12. In a drum for washing machines, the combination of heads, a wall having a door opening, a door pivotally mounted on the drum, and a baffle secured at its end to the heads and having a rounded portion adjacent the pivotal axis of the door and contacting with the rear edge of the door and a groove in which the end of said wall is located.

ALVA J. FISHER.
